UNITED STATES PATENT OFFICE

2,519,308

PORTABLE BUCKING TOOL

Morris Brown, San Diego, Calif.

Application March 9, 1945, Serial No. 581,863

2 Claims. (Cl. 78—53.5)

1

The invention relates to portable bucking tools for riveting through a power hammer which imparts blows to rivets engaging the tool.

The several objects of the invention are to provide a bucking tool; which is light in weight to reduce fatigue of the operator and adapted for bucking heavy rivets; which comprises an elastic casing which functions to deaden sound and reduce the shock transmitted to the operator; in which the elastic casing also functions to damp the hammer imparted strokes to the bucking-head; for increasing the reactive strokes imparted to the head by the spring pressed anvil; which includes a simple and quickly detachable connection between the stem of the bucking-head and tube in which it is slidable for attaching bucking-heads of different shapes for use in different types of riveting or for rivets of different shapes and sizes; and other objects which will appear from the detail description.

The invention consists in the several novel features which are hereinafter set forth and more particularly defined by claims at the conclusion hereof.

In the drawings:

Fig. 1 is a longitudinal section of a tool embodying the invention, parts being shown in elevation.

Fig. 2 is a section taken on line 2—2 of Fig. 1.

Fig. 3 is a perspective of a bucking-head.

Fig. 4 is a detail perspective of the tube in which the stem of the bucking-head is slidable and in which the anvil is confined.

Fig. 5 is a longitudinal section of a modified form of the invention, parts being shown in elevation.

Fig. 6 is a perspective of the retaining member shown in Fig. 5.

Fig. 7 is a perspective of the tube shown in Fig. 5.

Fig. 8 is a section taken on line 8—8 of Fig. 5.

The invention is exemplified in a bucking tool which comprises a metal tube 10, the bore of which is cylindrical; a bucking-head 11 provided with a cylindrical stem 12 which fits into, is slidable in one end portion of the tube 10; and is provided with a longitudinally extending groove; an instruck resilient tongue 15 on the tube 10 which is adapted to extend and fit into the groove 14 in the stem and slidably retain the head 11 in connected relation, and against rotation relatively, to the tube 10; cylindrical anvil 16 slidably fitting in the tube 10; a spring 17 acting on the anvil 16 to impart counter-blows to the head 11 reactively to the impact blows from the ham-

2

mer; and a casing 19 formed of elastic material, such as rubber which fits snugly around the outer periphery of tube 10 and is provided with a closed end 20 the inner face of which is engaged by spring 17. The tongue 15 and groove 14 are shaped to permit the stem 12 to be inserted into the tube 10, so the tongue will snap into groove 14 and predeterminedly limit the outward movement of the anvil 16 by its spring 17, when the stem 12 is withdrawn from tube 10, and to adapt the stem 12 to be slidable inwardly from the impact blows derived from the hammer through the rivets. The tongue 15 fits in and extends across the groove 14 so the tube and stem will be relatively non-rotatable. This exemplifies a simple construction for quickly and interchangeably connecting bucking-heads of different shapes which are adapted for different forms of riveting or riveting rivets of different shapes and sizes. The tongue 15 normally arrests the outward movement of the stem 12 by the spring-pressed anvil 16, the spring 17 being under compression when the bucking head 11 is connected to the tube 10. The tongue is also adapted to be cammed out of groove 14, when preponderating force is applied to the head for its removal from the tube, and the inner end of the stem is adapted to spring the tongue outwardly when the stem is forced into the tube. This exemplifies a snap-connection for easily and quickly and interchangeably connecting bucking-heads for different kinds of work, to the tube containing the spring-pressed anvil.

The tube 10 terminates inwardly from the end of the elastic casing 19 adjacent the head 11 and a washer 22 of metal surrounds stem 12 between said end of casing 19 and a shoulder 23 on the head 11. The impact blows imparted from the hammer through the rivets to the head 11, cause the shoulder 23 to engage the washer 22 and the latter to engage the contiguous end of the elastic casing 19. This damps the inward movement of the head 11 resulting from the impact blows imparted to the head, and causes the spring-pressed anvil to rebound from, and impart more effective counter-blows to the stem 12 on head 11. This accelerates the upsetting of the rivets and effects a saving of time in riveting operations. The masses in the head and in the anvil, and the force of spring 17 are co-related so as to tend to synchronize the hammer blows and the counter-blows.

The elastic casing 19 which is gripped by the operator in bucking the rivets, suppresses or deadens the noise or sound resulting from the

impact and counter-blows and also cushions these blows, to lessen fatigue and shock in the use of the tool. The casing 19 may have its outer periphery annularly grooved, as at 24, for firm gripping in the hands of the user.

The operation of the bucking tool is as follows: the user will insert into the open end of tube 10 the stem 12 of a bucking tool having a face shaped for the particular class of riveting desired, the tongue 15 will snap into groove 14 and 10 slidably and non-rotatably hold the head 11 in operative relation with the tube 10 and casing 19. This construction greatly facilitates interchange of heads for different classes of riveting. The operator, gripping the casing 19, will hold 15 the outer face of head 11 against a rivet which has been inserted through the work to be riveted. Hammer blows will be imparted to the rivet by another operator, which will be transmitted through the rivets to the head 11, for upsetting the inner end of the rivets. These blows will be transmitted by the head 11 to the anvil 16, causing the latter to rebound from the stem 12 against the force of spring 17. The spring will cause the anvil to reactively impart outward 20 blows to the head. During the inward strokes of the head, shoulder 23 will engage washer 22, which will compress the inner end of elastic casing 19 to damp the vibrations of the head, for rendering the counter-blows on the stem from the anvil more effective and for accelerating the riveting operations. During these riveting operations the noise produced will be deadened or suppressed by the elastic casing which will also 25 reduce transmission of the vibrations in the tube 10 resulting from the impact and counterblows. This greatly reduces fatigue of the operator.

In the modification of the invention illustrated in Figs. 5 to 8, the tube 10', is provided with a longitudinal slot 26, the stem 12 of the bucking-head 11' is provided with a groove 14', and a retaining member 27 extends through slot 26 into and yieldingly held in groove 14' by the elastic casing 19', and is provided with abutments 28 which engage the tube 10' at the ends of slot 26 45 for retaining the member 27 in the tube when the stem 12 is withdrawn from the tube. This exemplifies a snap connection for the tube and stem in which the retaining member is yieldingly held in the stem by the elastic casing. A cap 30 50 is secured by a pin 31 in the outer end of tube 10', and functions as a closure for said end of the tube and as an abutment for the spring 17 which presses against the anvil 16. The outer end of the elastic casing 19' terminates at the 55 cap 30. The inner end of the casing 19' extends beyond the inner end of the tube 10' for the purpose before described. The operation of this modified form of the invention is similar to the operation of the other construction.

The invention exemplifies a portable bucking tool which comprises an elastic casing which reduces the fatigue of the operator; is light in weight; is adapted for comparatively heavy work; accelerates the riveting operations; a snap connection between the tube and the bucking-head which permits easy and quick interchange of heads for different kinds of work; reduces the 60

noise incident to the riveting operations; and is simple in construction and efficient in operation.

The invention is not to be understood as restricted to the details set forth since these may be modified within the scope of the appended claims without departing from the spirit and scope of the invention.

Having thus described the invention, what I claim as new and desire to secure by Letters Patent is:

1. A portable bucking tool for co-acting with a power-hammer, comprising: a tubular member open at its inner end, a bucking head provided with a face for engaging a rivet and receiving impact blows from the hammer to the rivet, and with a stem slidably mounted in the tubular member, an anvil for the stem confined in the tubular member, a spring at the inner end of the tubular member acting on said anvil, means for slidably retaining the stem in the tubular member, and a tubular casing of sound-deadening material around and jacketing the tubular member substantially throughout its entire length, forming a supporting grip for manipulating the tool and having an integral end-portion forming a seat for said spring.

2. A portable bucking tool for co-acting with a power-hammer, comprising a tubular member, a bucking head provided with a face for engaging a rivet and receiving impact blows from the hammer to the rivet, and with a stem having a longitudinal groove in its periphery slidably mounted in the tubular member, a spring-pressed anvil for the stem confined in the tubular member, the tubular member having a portion with slot and an integral resilient struck tongue extending into said groove for slidably retaining the stem in the tubular member, and a tubular casing of rubber fitting around and jacketing the tubular member substantially throughout its length, forming a cover for the slot and forming a resilient grip for manipulating the tool, the casing being extended around said tongue.

MORRIS BROWN.
